VALENTIN JOSEPH MOHLER, OF BROOKLYN, NEW YORK, ASSIGNOR TO UNDERWOOD TYPEWRITER COMPANY, OF NEW YORK, N. Y., A CORPORATION OF DELAWARE.

TYPE-WRITING MACHINE.

1,096,791.

Specification of Letters Patent. Patented May 12, 1914.

Application filed April 10, 1911. Serial No. 619,980.

To all whom it may concern:

Be it known that I, VALENTIN JOSEPH MOHLER, a citizen of the United States, residing in Brooklyn, in the county of Kings 5 and State of New York, have invented certain new and useful Improvements in Type-Writing Machines, of which the following is a specification.

The present invention relates to mechanism for clutching the platen of a typewriting machine to the line-spacing device, to provide for the usual uniform line-spacing of the platen; and for releasing the platen from the line-spacing device to permit of 15 independent movement of the two, so that fractional or irregular adjustment of the platen may be effected when desired.

An object of the invention is to provide, for the purpose stated, a clutch which will 20 grip the platen to the line-spacing device in numerous positions; and which, in so gripping the platen, will not disturb the adjustment thereof, but on the contrary will hold the platen positively in such manner that 25 no play of the parts or disturbance of the adjustment can take place until the clutch is again operated to release the platen for another adjustment.

It is a feature of the invention that by 30 means of the same the platen may be adjusted with extreme finesse. It is characteristic of the invention that the mechanism forming the same may be of few and durable parts, compact in structure, neat in appearance, and absolutely reliable in operation.

In the preferred form of the invention, it is the platen which is permanently secured to the platen shaft, and the line-spacing wheel which is locked to and released 40 from the shaft in the operation of the device. The clutch is shown as comprising a pin or detent carrying member, and a pin hole, or recessed plate, these two elements being relatively shiftable into and out of 45 locking engagement. In the preferred form, the detent carrying member is secured to the platen to rotate therewith at all times, and the recessed plate is secured to the line-spacing wheel; and in this form 50 it is preferably the detent carrying device which is shiftable in the operation of the invention.

A feature of the invention is the novel arrangement of pin holes or recesses in one of 55 the clutch members, and the arrangement of

the pins or detents in the other clutch member. This arrangement of the pin holes and pins permits of the employment of a great number of these locking elements; and it is largely to this feature that the substantial 60 accuracy of adjustment and certainty of locking action may be ascribed.

Other features and advantages will hereinafter appear.

In the accompanying drawings, Figure 65 1 is a perspective view of the assembled mechanism. Fig. 2 is a view in cross section of the mechanism, the parts being shown in normal position with the platen locked to the line-spacing wheel. 70 Fig. 3 is a view similar to Fig. 2 except that the parts are in platen releasing position. Fig. 4 is a view in cross section on the line 4—4 of Fig. 3 looking in the direction of the arrow *a*. Fig. 5 is a view in cross section on the line 5—5 of Fig. 3 looking in the direction of the arrow *b*. Fig. 6 is a detail view in cross section of Fig. 8, illustrating the locking of the line spacing wheel by two lock pins. Fig. 7 is a view in cross section 80 on the line 7—7 of Fig. 2 looking in the direction of the arrow *c*. Fig. 8 is a detail view looking at the face of the pin hole plate and showing the relative position of lock pins and pin holes in one adjusted position of the platen. Fig. 9 is a detail view 85 showing one group of six of the lock pin springs formed from a single piece of metal.

Mounted in the carriage 1 is a platen shaft 2, carrying a platen 3, a hand wheel 4, and a line-spacing wheel or disk 5. The line-spacing movement of the wheel 5 is effected as in the Underwood machine by means of a pawl 6 carried by a slide 7 which is operated by a line-spacing lever 8. A spring 9 90 returns the slide to normal position after each operation; and a spring detent 10 holds the line-spacing wheel with the platen in the positions to which the same are fed.

The hand wheel is made fast to the platen shaft by means of a set screw 11 which extends through a hub 12 of the hand wheel. The line-spacing wheel 5 is not mounted directly upon the platen shaft 2 but is carried by a cup or casing 13 which rides upon a sleeve 15 secured to the shaft by means of a pin 16. The line-spacing wheel is threaded at 17 onto the cup 13 so that in the operation of the device, the line-space wheel and cup act as a unit, the cup 13 and wheel or 110

disk 5 together form an inclosing casing within which the clutch mechanism is housed, the disk 5 forming a cap or cover plate for the cup 13.

5 The parts thus far described provide for the permanent attachment of the hand wheel to the platen, but permit of relative rotary movement of the platen and line-spacing wheel. Normally, however, the line-spacing 10 wheel is locked to the platen shaft so that the line-spacing movements of the platen may be effected from the spacing wheel in the usual manner; and for this purpose there are a number of lock pins or detents 15 18, which, when the structure is assembled, permanently engage a disk 23 fast to the sleeve 15, and are shiftable into and out of corresponding holes or recesses 24 in the inner face of the cup 13, thereby locking and 20 unlocking cup 13, which carries the ratchet wheel, and sleeve 15, which is fast to the platen shaft. This shifting movement of the lock pins 18, in a direction parallel to the platen shaft, is effected by means of a 25 second disk 19 which is longitudinally movable on the platen shaft, and which will be referred to as the pin carrying disk.

The pins 18 are not fast to the disk 19 but are mounted to yield perpendicularly thereto. The pins pass entirely through the disk 19 and have heads 18^a against each of which there bears a leaf spring 20, tending to hold the head of the pin against the face of the carrying disk. The springs 20 are secured 30 to the pin carrying disk between the latter and plates 21 by means of screws 22. The pins are arranged in groups as shown in Fig. 7, and this grouping provides for the location of the plates 21 which hold the 35 springs 20. For convenience, the springs 20 are made in units of six each from pieces of the spring material, as shown in Fig. 9. To prevent angular displacement of the plates 21, the ends 30 of the same are pointed and 40 hooked over to engage in corresponding recesses in the disk 19. There are shown three plates 21 each holding three pairs of springs 20, the number, length, and disposition of the springs corresponding to the number 45 and arrangement of the locking pins.

To unlock the line-spacing wheel from the platen shaft so that the latter may be independently adjusted, it is merely necessary to shift the pin carrying disk 19 from Fig. 2 50 to Fig. 3 position, this movement being sufficient to cause the withdrawal from the face of cup 13 of any pins 18 which may have been in engagement with pin holes 24 in the face of the cup. The disk 19 is normally 55 held in platen locking position by means of a coil spring 25 which bears at one end against the line-spacing wheel and at its other end against the disk 19 tending to urge the latter toward the inside face of the 60 cup. The shifting of the disk 19, against 65

the action of the spring 25, is effected by means of a push button 26. This push button carries a pair of plungers 27 which extend through passages in the hub 12 of the hand wheel, and through corresponding 70 passages 28 in the sleeve 15 on which the ratchet wheel rides so as to bear at their inner ends against the pin carrying disk. The plungers are of two diameters to provide shoulders 27^a which, by engagement 75 with the inner face of the hand wheel hub 12, serve as stops to determine the normal position of the pin carrying disk, and to limit the throw of the same under the action of the spring 25. When the push button 80 26 is moved toward the platen, this movement is transmitted by the plungers 27 to the pin carrying disk. After a movement of the pin carrying disk, sufficient to release the platen, the push button is stopped by 85 engagement with the face of the hand wheel hub; and the pin carrying disk is then held against movement in platen releasing position, by the plungers 27 on the one hand, and by the spring 25 on the other hand. 90 So long as the pressure is maintained on the push button, the platen may be freely turned independently of the line-spacing wheel; and any desired adjustment of the platen 95 may be effected. After the adjustment of the platen has been effected, the push button is released, and the coil spring 25 throws the pin carrying plate toward the inner face of the cup 13 to lock the platen, and in so doing returns the push button to 100 normal position.

The lock pins are arranged in three groups of six pins each as shown in Fig. 7. The pins are located at three different radial distances from the axis of the clutch, there 105 being two pins in each group, or six pins in all, which are equidistant from the clutch axis. The lock pin holes 24 in the cup 13 are arranged in three concentric circles, the radii of which circles correspond respectively to the three radial distances separating the pins from the clutch axis. There are twenty-three holes in each circle as shown in Fig. 4, the pin hole centers in each circle 110 being spaced at equal angular distances. The pin centers are also methodically positioned around the clutch axis but with angular spacing which differs from that of the pin holes. The disposition of the lock pins with respect to the pin holes is such that no 115 two of the eighteen lock pins can simultaneously truly center with a lock pin hole. If one pin is so centered, then all of the other pins are more or less off center with respect to the opposing lock pin holes. The 120 arrangement of the pins and pin holes is an adaptation of the idea of the vernier gage, where the pins may for purposes of illustration be viewed as the vernier divisions, and the pin holes as the divisions on 125 130

the other scale, or vice versa. With this idea in mind, it follows that when one pin is centered with a hole, another pin is almost centered, and the other pins are off center 5 by gradually increasing amounts. As shown in Fig. 6, the pins have conical ends 31, so that even though the pin may be off center with respect to the opposing hole, it may nevertheless enter that hole to an extent 10 depending upon the amount by which the pin is off center. If sufficiently off center, the pin may strike the plate of the cup 13 between two holes, and cannot enter any hole. The pins are yieldably mounted in 15 the pin carrying disk 19 so that the disk may be given its full throw even though many of the pins are stopped at the surface of the cup plate or can enter the pin holes to a slight extent only. Since there 20 are twenty-three holes in each of the concentric circles in the cup 13 (see Fig. 4), it follows that there are twenty-three adjusted positions of the platen in which the same one pin can be centered with some pin 25 hole: and since there are eighteen pins and the numbers 18 and 23 are prime to each other, it follows that there are 18×23 , or 414 adjusted positions of the platen in which there will be a pin which centers with a 30 hole. If any one pin is truly centered such pin will resist efforts tending to disturb the adjustment; but one pin alone unless truly centered would not only not prevent disturbance of the adjustment, but by reason 35 of its spring pressure would assist in such disturbance. One pin alone, however, whether truly centered or not, is not necessarily relied upon in the present invention to prevent disturbance of adjustment: every 40 pin that to any extent projects into a pin hole assists in the holding of the platen fixed with respect to the line-spacing wheel. Referring again to the vernier, it will be remembered that when one vernier division 45 registers with a division on the other scale, those vernier divisions to one side will be off center by increasing amounts in one direction; whereas those divisions to the other side will be off center in the other direction. 50 So in the present invention, certain of the pins will be off center on one side of the pin holes, and certain others off center on the other side. The result is as indicated in Fig. 6, from 55 which it will be seen that wherever two pins are off center on different sides, the cup plate 13 is positively clamped or held against movement between the pins. This locking action exists not only for one pair 60 of pins but for all the pins except those which by striking the surface of the cup plate are prevented from entering any hole. Reference has been made to four hundred and fourteen adjusted positions of the platen 65 in which some one pin is centered, and in

which the locking is assisted by other pins partially projecting into their pin holes. It does not follow however, that there are but four hundred and fourteen possible adjustments of the platen. The number of possible adjustments is very great for, even though no pin truly centers in any hole, still the conditions indicated in Fig. 6 can readily occur. 70

The mechanism above specifically described may be variously modified within the scope of the invention. The style of pin or detent and of the recesses therefore may be varied; and the positioning and mounting of the clutch members may be 80 reversed or otherwise changed so long as their proper relations are maintained, without involving a departure from the invention. 85

Having thus described my invention, I claim:

1. In a typewriting machine, the combination of a platen shaft, a platen on the shaft, a line spacing wheel, a cup by which said line spacing wheel is carried, said cup being 90 mounted to permit of rotation thereof relatively to the platen, and having a recessed inner face, a pin or detent carrying device secured to the platen against rotation with respect thereto contained within said cup 95 between the recessed face thereof and the line spacing wheel, and means for shifting said detent carrying device relatively to the recessed face of the cup to cause a detent on said device to engage and disengage a 100 recess in the cup.

2. In a typewriting machine, the combination of a platen shaft, a platen on the shaft, a line spacing wheel, a cup by which said line spacing wheel is carried, said cup being 105 mounted to permit of rotation thereof relatively to the platen, and having a recessed inner face, a pin or detent carrying device secured to the platen against rotation with respect thereto contained within said cup 110 between the recessed face thereof and the line spacing wheel, a hand wheel fast to the platen, a plunger extending through the hand wheel and through the inner face of the cup to bear against the detent carrying 115 device within the cup, whereby the detent carrying device may be moved away from the inner face of the cup to withdraw the detent from the latter to release the platen from the line spacing wheel. 120

3. In a typewriting machine, the combination of a platen shaft, a platen fast to the shaft, a line-spacing wheel, a pin or detent carrying device secured to the shaft to rotate as a unit therewith comprising a group 125 of axially movable detents, a single spring individually operating all the pins in said group, and means for shifting said detent carrying device longitudinally of the platen shaft to cause the detents of the detent car- 130

rying device to engage and disengage the line-spacing wheel.

4. In a typewriting machine, the combination of a platen shaft, a platen on the shaft, a line-spacing wheel means for releasably connecting the platen and line-spacing wheel comprising a surface having a plurality of recesses therein and a device carrying a plurality of axially movable pins or detents for engagement with the said recesses, said detents and recesses being arranged differently on their respective carriers whereby certain detents may be off center with respect to opposing recesses, while other detents are centered with respect to opposing recesses, a single spring individually operating a plurality of said detents, and means for shifting said detent carrying device longitudinally of the shaft between platen locking and platen releasing positions, to cause one or more of the detents to engage and disengage the said recesses.

5. In a typewriting machine, the combination of a platen shaft, a platen fast to the shaft, a line-spacing wheel, a group of axially movable pins or detents, a single spring individually operating the detents of said group, a pin or detent carrying device secured to the shaft to rotate as a unit therewith, a hand wheel fast to the platen, and a device carried by the hand wheel for shifting said detent carrying device longitudinally of the platen shaft to cause the detents of the detent carrying device to engage and disengage the line-spacing wheel.

6. In a typewriting machine, the combination of a platen shaft, a platen fast to the shaft, a line-spacing wheel, a group of axially movable pins or detents, a single spring individually operating the detents of said group, a pin or detent carrying device secured to the shaft to rotate as a unit therewith, a hand wheel fast to the platen, a plunger carried by the hand wheel for moving said pin or detent carrying device to disengage the detents thereof from the line-spacing wheel, and a spring for moving said pin or detent carrying device to cause the detents thereof to reengage the line-spacing wheel when the plunger is released.

7. In a typewriting machine, the combination of a platen, a line-spacing wheel, a clutch to releasably connect the platen and said wheel, said clutch comprising a disk having a plurality of circles of pin holes concentric with the platen axis, said clutch also comprising a member carrying a plurality of lock pins positioned at different distances from the platen axis, some of which distances correspond to the radius of one of the pin hole circles and the others of which distances correspond to the radius of another of the pin hole circles, there being a number of pins at the same radius and the pins being arranged in separated clusters

or groups, the pins on the one member being also so arranged with respect to the pin holes in the other member that when any one pin truly registers with its opposing pin hole, the other pins are off center with respect to their opposing pin holes by gradually increasing amounts, and means for shifting said clutch members relatively to each other along the axis of the clutch to cause the same to engage and disengage. 75

8. In a typewriting machine, the combination of a platen, a line-spacing wheel, a clutch to releasably connect the platen and said wheel, said clutch comprising a disk having a plurality of circles of pin holes 80 concentric with the platen axis, said clutch also comprising a member carrying a plurality of lock pins positioned at different distances from the platen axis, some of which distances correspond to the radius of one of the pin hole circles and the others of which distances correspond to the radius of another of the pin hole circles, there being a number of pins at the same radius and the pins being arranged in separated clusters or 90 groups, the pins on the one member being also so arranged with respect to the pin holes in the other member that when any one pin truly registers with its opposing pin hole, the other pins are out of register with respect to their opposing pin holes by gradually increasing amounts, means for shifting said clutch members relatively to each other along the axis of the clutch to cause the same to engage and disengage, and means secured 100 to the pin carrying member between the groups of pins thereon for resiliently holding said pins in position in said pin carrying member.

9. In a typewriting machine, the combination with a rotatable platen, of a line-space wheel, and a clutch forming a releasable connection between said platen and line-space wheel, said clutch comprising two coöperating members, one of said members 110 having a series of openings therein, a series of axially movable pins in the other member, a single leaf spring operating a number of said pins, and manual means for moving said pins. 115

10. In a typewriting machine, the combination of a platen shaft, a platen fast to the shaft, a line-spacing wheel, a clutch to form a releasable connection between the platen and said wheel, said clutch including a releasable clutching member comprising a group of axially movable pins secured to the shaft to rotate as a unit therewith, and a single spring individually operating all the pins in said group. 120

11. In a typewriting machine, the combination of a platen shaft, a platen on the shaft, a line-spacing wheel, a pin or detent carrying device secured to the platen to rotate as a unit therewith comprising a group 130

of axially movable detents, a single spring individually operating all the pins in said group, and means for effecting a releasing movement between said detent carrying de-

5 vice and line-spacing wheel.

12. In a typewriting machine, the combination with a rotatable platen and a line-space wheel, of a clutch comprising a part having a series of axially movable pins arranged in a plurality of concentric circles, and also comprising a part having a series of openings arranged in corresponding circles, the number of openings being materially greater than the number of pins, and 10 a pin-operating means including a single spring arranged to operate a plurality of said pins.

13. In a typewriting machine, the combination with a platen and a line-space wheel, 20 of a clutch comprising a member having numerous pins, and a member having a multitude of openings to receive the pins, the spacing of all of said openings having a differential relation to the spacing of all of the 25 pins, to permit but a single pin and opening to register at a time.

14. In a typewriting machine, the combination with a platen and a line-space wheel, of a clutch comprising a member having a 30 series of pins, and a member having a series of openings to receive the pins, said pins and openings being so spaced that when one pin registers with an opening, the remaining pins are out of register with their 35 adjacent openings by gradually increasing amounts, whereby a fine and practically universal adjustment of the platen relatively to the line-space wheel may be obtained.

40 15. In a typewriting machine, the combination with a platen and a line-space wheel, of a clutch comprising a member having a plurality of pins, and a member having a plurality of openings to receive the pins, 45 said pins and openings being so spaced that the number of positions in which a pin and opening register during a complete rotation of the platen relatively to the line-space wheel is the product of the number of 50 openings and pins.

16. In a typewriting machine, the combination with a platen and a line-space wheel, of a connecting clutch comprising a member formed with a number of annular series of 55 equally spaced openings, and a member having a plurality of pins including a pin or pins to register with each of said series, said pins being so spaced and positioned that only one pin and opening can register at 60 once.

17. In a typewriting machine, the combination with a platen and platen axle, of a cup or casing loosely mounted on said axle, a disk removably connected with the casing 65 and forming a cover plate therefor, teeth

surrounding the disk to form a line-space wheel, and clutch mechanism in said cup for connecting and disconnecting the latter from the platen axle.

18. In a typewriting machine, the combination of a platen, a cup, a disk removably connected to the cup to form a closure therefor, teeth on said disk to form a line-space wheel, and clutch mechanism housed within 70 said cup. 75

19. In a typewriting machine, the combination of a platen shaft, a platen on the shaft, a line-space wheel, connecting means between the platen and line-space wheel comprising a surface having a plurality of 80 recesses therein and a device carrying a plurality of pins or detents for engagement with the said recesses, a plate fast to the platen between the detent carrying device and the said recessed surface, said plate 85 having holes therein for guiding the detents of the detent carrying device, and means for shifting said detent carrying device and said surface relatively one to the other between the platen locking and platen releasing positions, to cause one or more of the detents to engage and disengage the said recesses.

20. In a typewriting machine, the combination of a platen shaft, a platen fast to the shaft, a line-space wheel loose on the shaft, 95 means on said wheel having a surface with a plurality of recesses therein, a device carrying a plurality of pins or detents for engagement with said surface, means for shifting said pin carrying device longitudinally 100 of the shaft to cause one or more of the pins thereof to engage and disengage the said recesses, and a plate fast to the shaft positioned between the pin carrying device and said surface, said plate being perforated to 105 permit the movement of the stop pins therethrough and being in engagement with said pins in the several shifted positions of the latter.

21. In a typewriting machine, the combination of a platen shaft, a platen fast to the shaft, a line-space wheel loose on the shaft, means on said wheel having a surface with a plurality of recesses therein, a device having yieldably mounted thereon a plurality 110 of pins or detents for engagement with said surface, means for shifting said pin carrying device longitudinally of the shaft to cause one or more of the pins thereof to engage and disengage the said recesses, and a 115 plate fast to the shaft positioned between the pin carrying device and said surface, said plate being perforated to permit the movement of the stop pins therethrough and being in engagement with said pins in the 120 several shifted positions of the latter.

22. In a typewriting machine, the combination of a platen shaft, a platen on the shaft, a line-spacing wheel, means for releasably connecting the platen and line- 130

spacing wheel comprising a surface having a plurality of recesses therein and a device carrying a plurality of axially movable pins or detents for engagement with the said recesses, said detents and recesses being arranged differently on their respective carriers whereby certain detents may be off center with respect to opposing recesses, while other detents are centered with respect to opposing recesses, a single spring individually operating a plurality of said detents, and means for causing one or more of the detents to engage and disengage the said recesses; said pins or detents being mounted to permit the same to yield on their carrier upon striking the said surface.

23. In a typewriting machine, the combination of a platen shaft, a platen on the

shaft, a line-spacing wheel, an element carried with said wheel and having a plurality of recesses therein, a device carrying a plurality of axially movable pins or detents for engagement with the recesses in said element, a plate fast to the platen and thereby held against rotation relative to the platen, said plate having holes therein for guiding the detents of the detent carrying device, and means for causing one or more of the detents to engage and disengage the recesses in said element, said detents being arranged to lock the platen and line-spacing wheel in any relative position of adjustment.
